(57) **CLAIM**

The ornamental design for a plant cover, as shown and described.

DESCRIPTION

FIG. 1 is a perspective view of a plant cover showing my new design;

FIG. 2 is front view thereof;

FIG. 3 is a back view thereof;

FIG. 4 is a left view thereof;

FIG. 5 is a right view thereof;

FIG. 6 is a top plan view thereof;

FIG. 7 is a bottom plan view thereof; and,

FIG. 8 is an enlargement view of FIG. 1.

The dash-dash broken lines of FIGS. 1 and 8 depict the limits of the enlarged view and form no part of the claimed design. The dash-dash lead lines in FIG. 1 labeled 8 indicate the area from which the enlargement in FIG. 8 is taken and form no part of the claimed design.
